TABLET ARM CHAIR

Trace S. Christenson, Jr., South Bend, and Howard B. Barber, North Manchester, Ind., assignors to Peabody Seating Company, Inc., North Manchester, Ind., a corporation of Indiana

Filed Nov. 28, 1958, Ser. No. 53,565

Term of patent 14 years

(Cl. D33—11)

Fig. 1

Fig. 2

Fig. 3.

FIG. 1 is a side view of a tablet arm chair, showing our new design;

FIG. 2 is a top plan view of the same; and

FIG. 3 is a rear view of the same.

The dominant features of our design reside in those portions shown in full lines on the drawings.

We claim:

The ornamental design for a tablet arm chair, substantially as shown and described.
